UNITED STATES PATENT OFFICE.

PHILIP E. EBRENZ, OF ST. LOUIS, MISSOURI, ASSIGNOR TO JOHN DEERE
PLOW COMPANY, OF ST. LOUIS, MISSOURI, A COPARTNERSHIP.

VEHICLE.

No. 825,641.

Specification of Letters Patent.

Patented July 10, 1906.

Application filed October 23, 1905. Serial No. 283,927.

To all whom it may concern:

Be it known that I, PHILIP E. EBRENZ, a citizen of the United States, residing in the city of St. Louis and State of Missouri, have 5 invented certain new and useful Improvements in Vehicles, of which the following is a full, clear, and exact description, reference being had to the accompanying drawings, forming part of this specification.

10 My invention relates to an improvement in vehicles, and it has particular reference to binding and bracing members by which the joints of the seat-frames of the vehicles are reinforced, strengthened, and held from separation.

15 Figure I is a perspective view of a vehicle-body and seat-frame with my improvement applied thereto. Fig. II is an enlarged top or plan view of a portion of the body and 20 seat-frame, showing my improvement applied thereto. Fig. III is a front elevation of the parts shown in Fig. II. Fig. IV is a perspective view of my binding members.

25 A designates the body of a vehicle, such as 25 a buggy, and B the seat-frame-supporting risers surmounting the sides of said body.

C designates the side posts of the body-frame, by which the seat-frame of the vehicle is supported.

30 D designates the front and rear stretcher-rails, and E the side rails of the seat-frame. These rails are joined to each other in any common manner, preferably by mortise-joints, and when so united they are in the 35 absence of any binding or bracing means extremely liable to become separated during the use of the vehicle, and to prevent such separation I utilize the binding and bracing members, which I will proceed to describe.

40 1 designates binding-straps which have narrow leg portions that are adapted to be secured to the side posts C of the vehicle-body by suitable means, such as bolts or screws. These straps have widened upper vertical 45 portions 2, that are adapted to fit against and be secured to the front and rear stretcher-rails D. Extending laterally from the upper portions 2 are lips 3, which are adapted to extend over onto the upper edges of the front 50 and rear stretcher-rails, to which they are adapted to be secured, and onto the joints at the mating corners of the front and rear stretcher-rails and the side stretcher-rails. The straps 1 are also provided at their upper

ends with tongues 4, which extend from the 55 lips 3 over the side stretcher-rails and the risers B. These tongues are adapted to be secured to the side stretcher-rails, and each tongue is provided with downwardly-extending spurs 5, which are adapted to be driven 60 into the risers B.

It will be seen that by the described construction the straps 1 may be firmly secured to the side posts of the vehicle-body, the front, rear, and side rails of the seat-frame, 65 and also serve to connect the seat-frame to the risers of the body, due to the spurs 5 being embedded in said risers. By this means the joints of the seat-frame of the vehicle are rigidly held from separation, and the frame 70 is very efficiently tied to the body of the vehicle.

6 designates braces having their foot portions secured to the side posts of the vehicle-body and to the body side sills and also having their upper ends extending at angles to their foot portions and secured to the front and rear stretcher-rails. These braces by their particular attachment to the vehicle-body and the seat-frame stretcher-rails serve 75 to restrain the seat-frame from lateral movement, thereby relieving the seat-frame-supporting risers of strain.

I claim as my invention—

1. The combination with a vehicle-body 85 having side posts, and a seat-frame consisting of front, rear and side rails, of binding-straps secured to said posts and overlapping onto said rails at their junctions; said straps having lips secured to said front and rear 90 stretcher-rails and tongues secured to said side stretcher-rails, substantially as set forth.

2. The combination with a vehicle-body having side posts, and a seat-frame consisting of front, rear and side rails, of binding-straps secured to said posts and overlapping onto said rails at their junctions; said straps having lips secured to said front and rear 95 stretcher-rails and tongues secured to said side stretcher-rails, and said tongues being 100 provided with spurs adapted to enter the vehicle-body, substantially as set forth.

3. The combination with a vehicle-body having risers surmounting its side walls and having side posts, and a seat-frame consisting of front, rear and side stretcher-rails, of binding-straps secured to said side posts and said stretcher-rails; said straps having over-

turned lips and tongues at their upper ends secured to said stretcher-rails, and said tongues having spurs arranged to enter said risers, substantially as set forth.

5 4. The combination with a vehicle-body and a seat-frame, of binding-straps secured to said body and said seat-frame and braces

connecting said body and said seat-frame, substantially as set forth.

PHILIP E. EBRENZ.

In presence of—
BLANCHE HOGAN,
Wm. H. SCOTT.
